CLAIM

The ornamental design for a packaging box, as shown and described.

DESCRIPTION

FIG. 1 is a front view of a packaging box, showing my new design.

FIG. 2 is a right-side elevation view thereof, the left side is an identical image of the right side.

FIG. 3 is a rear elevation view thereof.

FIG. 4 is a front, top, right side perspective view thereof.

FIG. 5 is a top plan view thereof.

FIG. 6 is a bottom plan view thereof.

FIG. 7 is a rear elevation view thereof, in an open condition.

FIG. 8 is a front elevation view thereof.

FIG. 9 is a left-side elevation view thereof.

FIG. 10 is a right-side elevation view thereof.

FIG. 11 is a rear, bottom, left-side perspective view thereof; and,

FIG. 12 front, top, right-side perspective view thereof. In the drawings, the broken lines represent portions of the article which form no part of the claimed design.
